GOLF PUTTING PRACTICE DEVICE

Zuce Kogan, Chicago, Ill., assignor to Jef Manufacturing Co., Chicago, Ill., a corporation of Illinois

Filed Feb. 8, 1962, Ser. No. 68,732

Term of patent 14 years

(Cl. D34—5)

FIG. 1 is a perspective view of a golf putting practice device, showing my new design; and

FIG. 2 is a side elevational view of the same taken from the right-hand side of FIG. 1.

I claim:

The ornamental design for a golf putting practice device, substantially as shown.
